UNITED STATES PATENT OFFICE.

ADAM M. FRIEND, OF RAWLINS, WYOMING TERRITORY.

MANUAL MOTOR.

SPECIFICATION forming part of Letters Patent No. 364,406, dated June 7, 1857.

Application filed May 11, 1886. Serial No. 201,884. (Model.)

To all whom it may concern:

Be it known that I, ADAM M. FRIEND, of Rawlins, in the county of Carbon, Wyoming Territory, have invented a new and useful Improvement in Manual Motors, of which the following is a specification.

The invention is a combined hand and foot power motor, for use for driving printing-presses or other light stationary machinery; also for propelling vehicles of various kinds. It is so constructed that both the weight and strength of the operator may be applied and utilized for propulsive effect.

The invention is fully described hereinafter, and the features of patentable novelty indicated in the claims.

In the drawings, Figure 1 is a side view with one of the sides of the frame detached. Fig. 2 is a plan view, the levers being, however, not in exactly the same position as in Fig. 1. Fig. 3 is a detail view showing an alternative position of one of the hand-levers and its pawl.

In the frame F are journaled three horizontal shafts, Nos. 1 2 3. No. 1 is the driving-shaft; No. 3, the shaft from which power is taken off, and No. 2 is the intermediate or power-transmitting shaft. On the shaft 1 is fixed a driving-gear, G, which meshes with a pinion, P, on shaft 2, and a gear, G², on the latter in turn meshes with a pinion, P², on shaft 3. In this arrangement of shafts and gears there is of course no novel feature.

The operator of this motor bestrides seat S, so that his feet rest on and work the two treadle-levers T, while he grasps the two hand-levers H. These two sets of levers are journaled loosely on shaft 1, there being one treadle-lever and one hand lever on each side of the driving-gear G. In the forks of the levers is a cog-wheel or ratchet, R, which is fixed on shaft 1. Each hand-lever H has a pawl, p, that is pivoted in its fork, the latter being of sufficient length, relatively, to allow said pawl to swing through it, so that the lever may be worked either way to rotate the gear G in either direction. The alternative position of the pawl is shown in Fig. 3. The free or working end of the pawl p is made flat, so that right-angled shoulders are provided to engage the teeth

of wheel R. The treadle-levers T also have pawls p² pivoted in their forks, and adapted to likewise engage the toothed wheels R. Foot-levers f are pivoted in the outer ends of treadle-levers T, and the part of them that projects above the pivot serves as a foot block or rest, and the longer arm below acts on the pawl p² to raise it into engagement with the wheel R.

To support each treadle T in position to be conveniently reached by the feet of the operator, also to raise it after each depression, I employ a spiral spring, s, which is pendent from a rocker, r, pivoted on seat S. Obviously, when no pressure is applied to foot-levers f, the pawls p² will hang down out of action, and the hand-levers H may be used alone to operate the motor; or one treadle T may be used alone, or one hand-lever and treadle may be used together, or both treadles and both hand levers, as preferred or required. Thus the operator may apply little force, or as much as he is capable of, according to conditions. It will be noted that when he pulls on a hand-lever, H, he will naturally press downward with his foot on a treadle-lever, thus applying force with both, and to a greater degree than would be otherwise possible. In brief, both the weight and strength of the operator are utilized in direct application of force to the motor.

As before intimated, the pawls of hand-levers H may be swung over the shaft 1 and the levers worked from a seat (not shown) placed on that side. Other treadles may be also provided on the side opposite that where the seat is shown located.

What I claim is—

1. In a mechanical motor, the combination of a freely-vibrating hand-lever and a treadle having pawls, as shown, with a toothed wheel, and a rotatable shaft on which the toothed wheel is fixed and from which shaft power is transmitted, as set forth.

2. In a mechanical motor, the combination, with a driving-shaft, 1, having toothed wheels R fixed thereon, of the hand-levers H and treadle-levers T, having pawls adapted to engage said wheels, and means for supporting said treadle-levers, as shown and described.

3. The combination, with the driving-shaft 100

1, having toothed wheels R fixed thereon, of hand-levers H, which are hung loosely on said shaft and constructed with forks embracing said wheels, and the pawls which are pivoted in said forks and made of the length specified, whereby the levers are adapted to be reversed for the purpose of working the motor in the reverse direction, as set forth.

4. The combination, with a shaft and toothed wheel, of the treadle-lever T, a pawl and foot-

lever, f, pivoted thereto, the latter being arranged as specified, whereby it is adapted to raise the pawl into engagement with said wheel when pressure is applied to the foot-lever, as shown and described.

ADAM M. FRIEND.
